UNITED STATES PATENT OFFICE.

CARL W. SWANSON, OF CHICAGO, ILLINOIS.

WASHING-MACHINE.

1,250,528.

Specification of Letters Patent. Patented Dec. 18, 1917.

Application filed May 25, 1916. Serial No. 99,760.

To all whom it may concern:

Be it known that I, CARL W. SWANSON, a citizen of the United States, residing at Chicago, in the county of Cook and State of Illinois, have invented certain new and useful Improvements in Washing-Machines, of which the following is a specification.

My invention relates to improvements in washing machines, and more particularly to oscillating-tub machines.

Among the objects of my invention are to provide an efficient and simple oscillating washing tub especially well adapted for power-actuation and to provide improved means for bracing and draining and cleansing the same.

In the drawings, wherein I have shown an embodiment of my invention—

Figure 1 is a perspective view with parts broken away showing a tub embodying my invention;

Fig. 2 is a central vertical section on a plane including the line 2—2 of Fig. 1.

The improved tub shown comprises a body 10 having vertical end walls 11—11 each preferably braced by suitable bracing spider 12, attached thereto, the arms of which converge to a hub 13 from which protrudes a supporting pintle 14. The tub, of course, is mounted on its pintles in any suitable frame (as at 15) for oscillation. Suitable oscillating means, herein typified by the dotted lever 16 may be employed to oscillate the tub, and in practice the tub is best operated by power connection with an electric motor, so that it may receive a rapid, uniform movement through an angle of about 60 degrees.

In cross-section the tub is symmetrical with respect to its vertical axis in general design, and the flat end walls conform to the sectional design except for a bottom bracing extension. Preferably, in section, an upwardly flaring central mouth 17 meets, at each side, at an obtuse angle 17' a downwardly and outwardly extending belt 18 that angularly joins as at 18' a vertical mid-belt 19 which in turn joins, at 19', a lower belt 20 that preferably slopes inwardly toward the median line and connects at angle 20' with the bottom side-zone 21. Although the several zones may merge curvingly into each other, I prefer, for simplicity and efficiency, the angular arrangement shown. The bottom is preferably formed with two equal side zones 21 each having a drain-

slope down to its longitudinal center and connected at angles 21' with an apex-structure 23, reentrantly raised into the tub. In the form shown, this apex-structure has upwardly converging walls 24 that turn in horizontally in narrow shelves 25 connected by an arched mid-portion 26 that spans the center of the machine.

The end walls 11 preferably have bracing continuations 11^a inbent at their lower edges, 65 that close the ends of the reentrant apex-portion of the tub bottom, thereby strengthening the structure across its apex formation.

Along the angles 17' of the structure 70 where the side walls 17 of the mouth join the side belts 18, an inwardly extending horizontal flange 27 is provided, extending throughout the perimeter of the opening. This flange receives a coöperating cover 28, 75 preferably made of sheet-metal, that has its top arched or centrally elevated in transverse section and that has its lower portion in-bent horizontally to form a perimetral shoulder 29 for seating upon the flange 27. 80 At the sides of the shoulder 29 the cover-metal joins a down-bent extension 30 to form a vertical lip fitting neatly within flange 27. The end portions of the cover receiving flange 27 have downward continuations 27^a 85 that are bent back against, and preferably soldered to, the end walls of the casing as best shown at 31 in Fig. 1, thus giving to the ends of the cover-supporting flange a reinforced strength to resist down-bending. 90 The side portions of the flange 27 have guard-lip continuations 27^b vertically down-bent so as to lie close against the lips 30 of the cover. The lower edges of such guard-lips 27^b are out of contact with the adjacent 95 wall-portions 18 of the casing so as to leave spaces 32, in which up-thrown water, following the casing-sides when the tub is oscillated, may be caught and thrown back by the guard lips. A projection 35 on one flaring wall of the mouth structure 17 receiving under it one edge of the cover and coöperating latch and notch members 36 and 37, on the cover and the other wall of said mouth may effectively serve to lock the cover in 100 place when in use.

As a refinement adding to the practicability of the machine I provide on the sides of the body inwardly facing deflector ridges or projections 38 and 39, each preferably 110

a strip of metal angularly bent to provide a flat crest 40 and divergent deflector walls 41-41', having their bases soldered to the body, also, on the arched crest of the apex 5 26 I provide longitudinal ribs 42.

To extend centrally across the body beneath the reentrant apex structure I provide a draining and bracing structure 45, preferably in the form of a square tube. 10 Said tube has its rear end 46 lying within the apex and soldered flush against the wall 24 of the apex, and extends thence beyond the front of the body with a downward inclination, so that its bottom passes below 15 bottom zone 20 at the front of the machine. The top and side walls of the tube are cut away and joined, generally by soldering, as at 47, to the walls 24, 21 and 20 in front of the apex. The front end of this inclined 20 drain-and-brace tube is capable of being closed or opened as by a stop-cock 48. Openings 49 and 49' lead from the bottom areas on opposite sides of the apex to the drain channel, there being preferably a series of 25 perforations 49 substantially at the angle 20' at the front of the machine and another series of perforations 49' in the rear wall 24 of the apex close to the bottom angle 21' thereof. 30 For operation the tub is loaded with clothes and water, with a suitable detergent, to a level about the middle of the mid-belt 19, and then it is rapidly oscillated. At each stage or half of the oscillation of the tub a 35 large portion of the tub's contents is projected from the rising side to the falling side thereof, the water tending somewhat to follow the rising side of the casing, in obedience to centrifugal law, and being deflected by the ribs 38 and 39. The clothing-laden water, projected in large sheets and bodies, tends to trap air in the descending side of the body as a portion of the load is projected over the apex, and this 40 constant aeration stimulates the activity of the washing action, keeping the clothing from compacting, and giving access of the water and detergent to all parts of the clothing mass. At the ends of the machine where 45 the flange 27 has no guard-lip there is little chance for the water to escape, and the spaces 32 behind the guard lips 31 at the sides of the machine effectively prevent water from getting access to the front and back joints of the cover. Also these lips, and the coacting lips of the cover tend to 50 keep water from going up into the hollow interior of the cover, and the high-arched construction of the cover itself aids in this 55 operation of relieving the cover from shocks of water or clothing that would tend to dislodge it or throw undue strains on the cover latch. Heavy particles such as sand and other foreign matter settle to the bottom 60 of the casing under the violent agitation of 65

the non-compacted clothing and naturally such substances find escape through the openings 49 and 49' into the transverse tube 46. The contents of this tube are, as I find in practice, very little disturbed by the oscillation of the machine, as the tube is always full of water, its water-content is small, and it will be observed that no direct passage for washing to and fro of the water is provided in the connection of the tube with 70 this body, the openings on both sides of the apex being generally in a forward direction. In actual practice, foreign materials as sand, grit, etc., once trapped in this tube are held there until the washing operation 75 is finished. The tube thus located transversely of the apex at about its mid-length, adds greatly to the strength of the structure, and when the washing operation is over the machine may be drained while the tub 80 stands in horizontal position or with its front slightly depressed.

While I have herein described in some detail a particular embodiment of my invention, which I believe to be new and advantageous in detail, it will be apparent to those skilled in the art that numerous departures from the precise construction shown may be made without departure from the spirit of my invention and within the scope 90 of the appended claims.

Having described my invention, what I claim is:

1. A washing machine tub having, at its ends, bearing-members defining an axis of 100 oscillation, said tub being of greatest width in substantially the zone of said axis and tapering above and below the same, the bottom of said tub being formed into a reentrant apex structure and the end walls of 105 the tub overlying and bracing the ends of the inverted channel that is exteriorly formed by said apex-structure, and a separate tube transversely spanning the apex structure adjacent the middle of the length 110 of the latter and bracingly secured to the bottom portion of the tub, said tube extending beyond the front of the tub and provided with a drain cock.

2. A tub structure for an oscillating washing machine comprising a tub body having bottom zones 21 connected by a central apex structure, side walls diverging from said zones 21 to a mid-zone and converging above said mid-zone to a closable top-opening and 115 end walls having bearing members located centrally of the width of the tub, at about its greatest width; and a transverse tube exterior to and below substantially the middle of the length of the tub, said tube having its 120 rear end abutting against a reentrant wall of the apex, and extending below the front bottom-zone 21, the forward portion of said tube cut away at its top and sides to embrace the front zone 21 of the bottom and 125 130

being bracingly secured thereto, the front end of said tube projecting beyond the tub and having a drain-cock and said tube communicating with the interior of the tub 5 only through openings close to the front edges of both of the zones 21 of the bottom.

3. A tub for an oscillating washing machine having its side walls converging toward the top, having a top opening, surrounded by an inturned flange extending around the sides and ends of the opening, said flange having downbent continuations at its sides and ends, the side continuations 10 of the flange being spaced apart from the converging side walls of the casing and the end continuations of the flange being secured to the end walls of the casing to form braces.

4. A tub for an oscillating washing machine having its side walls converging toward the top, having a top opening, surrounded by an inturned flange extending around the sides and ends of the opening, said flange having downbent continuations 20 at its sides and ends, the side continuations of the flange being spaced apart from the converging side walls of the casing and the end continuations of the flange being divergently bent and secured to the vertical end 25 walls of the tub to form braces.

In testimony whereof I hereunto set my hand in the presence of two subscribing witnesses.

CARL W. SWANSON.
